UNITED STATES PATENT OFFICE.

ANDREW W. QUACKENBUSH, OF PERU, INDIANA.

SMOKE-JACK.

SPECIFICATION forming part of Letters Patent No. 349,318, dated September 21, 1886.

Application filed June 12, 1886. Serial No. 204,914. (No model.)

To all whom it may concern:

Be it known that I, ANDREW W. QUACKENBUSH, of the city of Peru, county of Miami, and State of Indiana, have invented certain new and useful Improvements in Smoke-Jacks, of which the following is a specification.

My said invention relates to that class of devices known as "smoke-jacks," which consist of a section of pipe with a flaring lower end connected to a stationary pipe secured in the roof of an engine-house or roundhouse, said flaring lower end being adapted to be dropped down over the upper end of the smoke-stack of a locomotive when in position in said house.

Said invention consists in devices for elevating and lowering said smoke-jack and securing it in the elevated or lowered position, as will be hereinafter more particularly described and claimed.

Referring to the accompanying drawings, which are made a part hereof, and on which similar letters of reference indicate similar parts, Figure 1 is a perspective view of the pipe, smoke-jack, and devices for operating said jack, the connection between said lever and smoke-jack being indicated by dotted lines; Fig. 2, a detail sectional view through the lever and its keeper, showing the upper portion of the handle in elevation, as seen from the dotted line 2 2 in Fig. 1; and Fig. 3, a horizontal sectional view, looking downwardly from the dotted line 3 3 in Fig. 2.

In said drawings, the portions marked A represent the smoke-pipe, B the smoke-jack, C the lever, D the handle, and E the keeper or catch-bar, with which projections on said handle may engage when said lever is pulled down, and the jack is consequently in elevated position. The pipe A and jack B are of substantially the usual construction, and need no special description. The lever C is mounted on a pivot or bolt, c, which passes through a bearing, a, secured to the side of the pipe, and itself passes through a slot in said bearing on said pipe to the inside, where it is connected by an appropriate link, C', (see dotted lines in Fig. 1,) to said smoke-jack or appropriate ears thereon. The handle D consists, principally, of a straight rod having an appropriate hand-hold at the lower end and projections d at the proper point near its up-

per end. It is connected to the lever C by a clevis, D'. The upper end of said rod extends through a hole in this clevis and has a head on its extreme upper end, which head has a projection, d', on one side, which is adapted to strike the sides of the clevis as said rod is given a quarter-turn in either direction. This projection is so arranged that when the rod is turned in one direction the projections d will be in line with the slot in the keeper or catch-bar E, through which said handle passes, and when turned in the other direction said projections will stand transversely to said slot. The keeper or catch-bar E is securely attached to the pipe A and extends out substantially the same distance as does the lever C. It is double, or has a slot formed therein through which the handle D passes. The operation is, when said lever is pulled down by means of said handle until the projections d are below said catch-bar, that by turning said handle said projections will stand transversely to said bar, and thus said bar will be kept from passing up through said slot, and the smoke-jack will be held in elevated position. When it is desired to drop the smoke-jack onto the smoke-stack of a locomotive, by simply giving this handle a quarter-turn the engagement between the projections d and the catch-bar E are released and the handle and lever can be moved upwardly, permitting said smoke-jack to descend as desired. Thus an efficient and simple means is provided for securing the smoke-jack in either of the desired positions.

Having thus fully described my said invention, what I claim as new, and desire to secure by Letters Patent, is—

1. The combination of the smoke-pipe, the smoke-jack, a lever pivoted to said smoke-pipe and connected to said smoke-jack, a handle having projections and capable of being rotated, and a catch-bar provided with a slot through which said handle passes, whereby, when said projections are brought into engagement with said catch-bar, the smoke-jack will be held in elevated position, substantially as set forth.

2. The combination, with the lever for operating the smoke-jack, of the handle D, secured to said lever by a clevis, D', said han-

dle being provided with the projections *d* and *d'*, and the slotted catch-bar *E*, through which said handle passes, substantially as set forth.

3. The combination of the smoke-pipe, the 5 smoke-jack, a lever pivoted to said pipe and connected to said jack, a handle having projections or catches thereon, and a catch-bar with which said projections may be brought into engagement, substantially as set forth.

In witness whereof I have hereunto set my 10 hand and seal, at Indianapolis, Indiana, this 8th day of June, A. D. 1886.

ANDREW W. QUACKENBUSH. [I. S.]

In presence of—

C. BRADFORD,
CHARLES L. THURBER.
